UNITED STATES PATENT OFFICE.

HENRY C. HANSEN, OF OAK HARBOR, OHIO.

POWER-JACK.

No. 905,177.

Specification of Letters Patent.

Patented Dec. 1, 1908.

Application filed June 29, 1907. Serial No. 381,413.

To all whom it may concern:

Be it known that I, HENRY C. HANSEN, a citizen of the United States, residing at Oak Harbor, in the county of Ottawa and State of Ohio, have invented certain new and useful Improvements in Power-Jacks; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to a power-jack such as may be employed for a variety of purposes such, for instance, as the tightening of large belts, the moving of heavy bodies and securing in place heavy loads.

My invention is designed to furnish a device of the character described which shall be cheap, light, strong, and useful for a great variety of purposes. I attain these objects by means of the devices and arrangement of parts hereinafter described and shown, and illustrated in the accompanying drawings, in which,—

Figure 1 is a top-plan view of my device; Fig. 2, a side-elevation of the same; Fig. 3, a side-elevation of the hand-lever hereinafter referred to; Fig. 4, a top-plan view of the same; Fig. 5, an end-view of the same with the handle in transverse section; Fig. 6, a top-plan view of the supplemental chain-wheel and its housing hereinafter referred to, on an enlarged scale; Fig. 7, a side-elevation of the same, and Fig. 8, a central transverse sectional elevation of the chain-wheels hereinafter referred to.

In the drawings, in which like numerals of reference indicate like parts, 1 is a housing composed of two like castings secured together at their opposite ends by bolts 3 and 4. A single integral casting forms a pair of ratchet-wheels 5 separated centrally by a chain-wheel 6. The casting has at opposite sides hubs 7 which fit loosely in openings in the sides of the housing, the openings being surrounded and reinforced by bosses 8. Through the ratchet-wheels, the chain-wheels, and the hubs is an axial opening 9 angular in transverse section. Through this opening may be passed a shaft 10 of corresponding angular cross-section the purpose of which will presently be described.

11 is a hand-lever having at its upper end

a handle 12 and having at its other end, formed integral therewith and at a right-angle thereto, a shaft 13 having its bearings in openings in the sides of the housings reinforced by bosses 14. Formed integral with the lever 11 and the shaft 13 are two circular lugs 15 disposed at opposite sides of the lever and eccentric to the axis of the shaft 13. The throw of these two eccentrics is diametrically opposite to each other. Mounted and journaled upon the two eccentrics 15 are pawls 16 the points of which are in alinement with and engage the teeth of the ratchet-wheels 5. It will be seen that when the lever 11 is swung upon its bearings in one direction one of the pawls will drive its ratchet-wheel forward while the other pawl retreats and that when the lever is swung in the opposite direction the movement of the pawls is reversed so that with each swing of the lever in either direction the ratchet-wheels are advanced a step. Secured to the housing at the end opposite the ratchet-wheels is a link 17 adapted for engagement with a chain, rope, or the like. The chain-wheel 6 is adapted to receive the links of a suitable chain which is passed around the wheel from the under side and forward over the end of the housing. Upon the inner side of the housing at its forward end is a cast-off block 18 which, as the chain is paid off from the chain-wheel, catches the links successively and disengages them from the teeth of the chain-wheel.

The operation of my device, thus far described, is as follows: Assuming for illustration that the device is to be used for moving a heavy load, the link 17 is anchored to an immovable object, a chain is secured to the object to be moved and passed under and over the chain-wheel 6. Now the swing to and fro of the lever 11 will, by the alternate action of the pawls 16, slowly and powerfully turn the ratchet-wheels and the chain-wheel and draw the load toward the anchor. As the successive links come in contact with the cast-off block 18 they are forced out of engagement with the teeth of the chain-wheel. To slacken the chain so that the jack may be disengaged from its load, the pawls are alternately lifted manually as they retreat from the teeth of their respective ratchet-wheels and held against engagement with the ratchet-wheel as they advance, thus permitting the ratchet-wheels to move backward step by step until the chain is suffi-

ciently slackened to permit its disengagement from its load.

19 is another housing practically identical with the housing 1 except that it has no provision for the journaling of the shaft 10 and is narrower for the reason that the sprocket-wheels are, in this instance, omitted. This housing is composed of two like parts secured together at their opposite ends by suitable bolts.

20 is a chain-wheel corresponding in number of teeth and diameter with the chain-wheel above described and having at opposite sides hubs 21 which fit loosely in the sides of the housings, the openings being surrounded and reinforced by bosses 22. Secured to the housing 19 is a link 23 adapted for engagement with a chain, rope, or the like. Upon the inner side of the housing 19 at its forward end is a cast-off block 24 which, as the chain is paid off from the chain-wheel, catches the links successively and disengages them from the teeth of the chain-wheel.

25 Through the center of the chain-wheel 20, transversely, is a hole 25 corresponding with the angular hole 9 through the chain-wheel 6 and in axial alinement therewith. Through the holes in the two chain-wheels may be 30 passed a shaft corresponding in cross-section with the angular holes 9—25. The two housings with their attachments may be slipped along the shaft any desired distance asunder. When the shaft 10 is rotated by means 35 of the lever, pawls, and ratchets mounted in housing 1, the two chain-wheels must rotate in unison and the chains having corresponding links engaged with such chain-wheels, must be caused to move uniformly.

40 A further application of my invention is illustrated in tightening or bringing together the ends of a broad heavy belt. The two housings with their attachments being placed upon the same shaft are placed a 45 suitable distance apart. The links 16 and 23

are secured by the usual clamping device to one end of the belt and the chains are passed around the chain-wheels 6 and 20 as above described and in like manner connected with the opposite end of the belt. Now by the 50 swing of the lever 11 to and fro the two ends of the belt are drawn powerfully together so that they may be laced or otherwise secured together.

Having described by invention, what I 55 claim and desire to secure by Letters Patent is,—

1. In a device of the described character, a housing, a shaft journaled in the housing, a pair of eccentrics on the shaft, a lever connected with the shaft, a pair of oppositely reciprocating pawls mounted and journaled upon the eccentrics, a pair of ratchet-wheels in operative relation to the pawls, a chain-wheel between the ratchet-wheels, said 65 ratchet-wheels being formed integral and having axially therethrough an opening angular in transverse area, and a shaft in said opening upon which the housing may be moved transversely. 70

2. In a device of the described character, a pair of housings, a chain-wheel in each of said housings, a pair of ratchet-wheels connected with one of said chain-wheels, a shaft upon which the two housings the chain-wheels and the ratchet-wheels are slidably mounted in rotative engagement, in one of said housings a shaft journaled in the housing, a pair of eccentrics on the shaft, a lever connected with the shaft, and a pair of oppositely reciprocating pawls mounted and journaled upon the eccentrics and disposed in operative relation to said pair of ratchet-wheels. 75 80

In testimony whereof I affix my signature 85 in presence of two witnesses.

HENRY C. HANSEN.
